KNITTING MACHINE

Paul W. Bristow, Laconia, N. H., assignor to Scott & Williams, Incorporated, Laconia, N. H., a corporation of Massachusetts

Original application December 30, 1948, Serial No. 68,114. Divided and this application June 17, 1950, Serial No. 168,813

5 Claims. (Cl. 66—165)

1

This invention relates to a knitting machine and has particular reference to a circular knitting machine of the superposed cylinder type.

This application is a division of my application Serial Number 68,114, filed December 30, 1948.

It is the object of the present invention to provide an improved slider control stop motion which will effect stoppage of the machine in the event that needle controlling sliders accidentally assume improper positions.

The foregoing and other objects of the invention particularly relating to details of construction and operation will become apparent from the following description read in conjunction with the accompanying drawings in which:

Figure 1 is a vertical axial section through the needle cylinders and the associated wrap yarn presenting mechanism of a knitting machine embodying the invention;

Figure 2 is a plan view showing various devices in the machine particularly the mounting of wrapping abutments, an arrangement for needle leveling and a slider controlled stop motion; and

Figure 3 is an inside development of various cams for control of rotating parts of the machine, certain of these parts being indicated in construction lines.

The knitting machine embodying the invention indicated above is of the superposed cylinder type comprising a lower cylinder 2 and an upper cylinder 3. Arranged to slide in slots in the lower cylinder are sliders 4 adapted to engage the lower hooks of double hook latch needles 6, the upper hooks of which are engageable by sliders 8 in the upper cylinder.

The lower sliders 4 are provided with butts at two levels 10 and 12. The upper sliders 8 are provided with butts at two levels 16 and 18. The cylinders are preferably provided with inserted fixed walls to define the slots for reception of the sliders and these walls 20 in the case of the upper cylinder terminate substantially above its lower end so that the lower portions of the slider slots are bounded not by stationary walls but by movable walls of two alternative forms arranged to slide in the wall slots in the upper cylinder. One set of these indicated at 22 carry butts 26 and are provided with out-

2

wardly and downwardly sloping lower ends as indicated most clearly at 30 in Figure 3. The other slideable walls indicated at 24 are provided with butts 28 and have verge bit extensions such as indicated at 32 in Figure 3. The verge bits are located between the positions of needles which, in the formation of broad ribs, are carried by sliders in the upper cylinder.

The cylinders are rotated and reciprocated in unison through the medium of a vertical shaft 34 which through conventional gearing is driven by the lower cylinder and which through gearing indicated at 40 and 42 drives the upper cylinder. The present machine additionally involves the driving of a wrapping assembly, which action is effected through gears 44 and 46, the former being carried by the shaft 34.

Arranged to cooperate with the needles are arcuate sinkers 48 which are provided with butts 50 arranged to be acted upon by stationary cams 52 supported by a stationary cylinder 54 inside the lower rotating cylinder. This stationary cylinder 54 also supports the fabric guiding tube 56 provided with an extension 57.

The rotary support for the wrap yarn carrying means is indicated generally at 58. It is secured to the gear 46 and includes a member provided with an annular groove 60 in which groove are received the rounded pivot-forming projections 62 of wrap yarn carriers 64 surrounded by spring bands 66 and 82. Dummy spacers 65 are provided in locations where wrap fingers are entirely missing so as to maintain proper tension conditions of the spring bands. Each of the wrap yarn carriers 64 has an upper extension 68 received in a notch 70 in an individual jack 72. These jacks 72 are provided with slots arranged so that they may embrace an annular ring 74 carried by the support 58. In order to guide the jacks 72 for radial movement and to position them in fixed circumferential locations they are received in slots 76 in the support 58. Each of the jacks is provided with a plurality of butts 73. These butts may be selectively broken away so as to provide selection in the operation of the wrap yarn carriers.

Each of the wrap yarn carriers 64 is provided with a downward extension extending through the upper cylinder and guided at its upper end

in a radial slot 80 in the support 58. The lower spring band 82 serves to urge the lower ends of the wrap yarn carriers inwardly. Butts 84 are provided on the wrap yarn carriers to provide for the positive inward movements of their lower ends and for the arrest of the outward movements of their lower ends.

At its lower end each wrap yarn carrier is provided with a radially directed extension 86 which has a downwardly extending branch 87 provided with the yarn guide openings 88. The downwardly extending branches 87 are provided with smooth lower inner edge portions arranged to cam the wrap yarn downwardly as the wrap yarn finger or carrier is withdrawn inwardly following a wrapping movement. Beyond these openings each carrier is provided with an abutment-engaging extension 90.

The foregoing describes in a general way the stitch forming elements which are present in the machine to which specifically the present invention is applied. Other details of general construction and operation may be found by reference to the parent application mentioned above.

Figure 2 illustrates the devices constituting a slider controlled stop motion. A member 550 carries a detector 552 in the form of a small, flat plate having a projection which on one side provides an abrupt shoulder 554 and on the other side a sloping cam edge 556. This detector projection has the position illustrated in the cam development Figure 3. It is located just above the level of the tops of sliders which are moving at welt level and circumferentially is located directly above the lower end of the run-down stitch cam. It is accordingly in position to be engaged and moved toward the left in Figure 2 by any slider which has not been pulled to welt level or below in a run-down direction. The member 550 is provided with a slot 558 which embraces a pin provided with a shouldered spacer 560 to hold the detector at the proper level. A notch 562 normally embraces a pin provided with a spacer 564. A rod 566 is linked to the left hand end of the member 550 as viewed in Figure 2 and is guided in a bracket 570, a compression spring 568 reacting between this bracket 570 and a shoulder on the rod 566. The arrangement is such as to hold the member 550 in a clockwise position limited by engagement of the trough of the notch 562 with its pin. A shoulder 572 on the member 550 engages a pin 574 projecting downwardly from an arm 576 carried by the shaft 577 which supports the conventional stop motion detector 578 which is arranged to detect the piling up of yarn in a needle hook or bent or flying latches as in press-off or the like. The shaft 577 operates the usual stop motion which is well known and need not be described in detail. The usual stop motion spring applied to this shaft urges it in counterclockwise direction so that the pin 574 normally maintains the member 550 in a right hand position limited by engagement of the left hand end of slot 558 with the pin passing therethrough. As will be evident this arrangement is such that a slider moving too high in the run-down direction will engage the shoulder 554 and by moving member 550 to the left will trip the stop motion. On the other hand, during a reverse stroke during reciprocatory knitting a slider will engage the cam edge 556 and merely rock the member 550 counterclockwise against the action of spring 568 without causing any tripping action.

During gore knitting, however, certain of the sliders will be raised out of action to the so-called

heel level and if special provision were not made these sliders would trip the stop motion. Accordingly, the gore sliders are provided with a slot 11 as indicated in Figure 3, which, when they are riding at heel level, will be lined up with the detector 552. The slots may accordingly pass the detector without tripping action.

However, since only the sliders in the gore sections have such a slot, if anything should happen so that more sliders are raised to heel height (for example, a jam or break of the main chain) the machine would be immediately stopped.

Also illustrated in Figure 2 are the wrap finger abutment 580 at the first wrap position and the wrap finger abutment 588 at the second wrap position. There are also shown in Figure 2 the latch opener 598 and the needle leveler blade 614. These elements are mounted and operate as described in the parent application referred to.

Figure 3 indicates the relationship of the stop motion to the lower cylinder forward stitch cam 650 and the clearing bolt cam 674.

The general operation of the machine is described in detail in the parent application referred to above. The operation of the stop motion has been described above. It will be apparent that the stop motion is effective to avoid smashes due to improper positioning of the lower sliders during operation.

What is claimed is:

1. A knitting machine comprising superposed needle cylinders, needles carried by said cylinders, sliders controlling movements of said needles, and a stop motion including a detector constructed and arranged to be engaged by sliders moving in one direction through an incorrect path to trip the stop motion, but to yield to the passage of sliders moving in the opposite direction without tripping the stop motion though the sliders are at a level corresponding to the level of the incorrect path in the first mentioned direction.

2. A knitting machine comprising superposed needle cylinders, needles carried by said cylinders, sliders controlling movements of said needles, and a stop motion including a detector constructed and arranged to be engaged by sliders moving in one direction through an incorrect path to trip the stop motion, certain of said sliders being provided with clearances so that they may pass said detector even though following a path incorrect for other sliders.

3. A knitting machine comprising superposed needle cylinders, needles carried by said cylinders, sliders controlling movements of said needles, and a stop motion including a detector constructed and arranged to be engaged by sliders moving in one direction through an incorrect path to trip the stop motion, but to yield to the passage of sliders moving in the opposite direction though the sliders are at a level corresponding to the level of the incorrect path in the first mentioned direction, certain of said sliders being provided with clearances so that they may pass said detector even though following a path incorrect for other sliders.

4. A knitting machine comprising superposed needle cylinders, needles carried by said cylinders, sliders controlling movements of the needles, said sliders comprising two sets, and a stop motion including a detector constructed and arranged to be engaged by sliders of one set moving in a predetermined path, which is incorrect for

said set of sliders, to trip the stop motion, said stop motion being ineffective upon passage of the sliders of the other set along said path.

5. A knitting machine comprising superposed needle cylinders, needles carried by said cylinders, sliders controlling movements of the needles, said sliders comprising two sets, and a stop motion including a detector constructed and arranged to be engaged by sliders of one set moving in a predetermined path, which is incorrect for said set of sliders, to trip the stop motion, said stop motion being ineffective upon passage of the sliders of the other set along said path but

effective upon passage of the sliders of said other set along an incorrect path.

PAUL W. BRISTOW.
